CONTROL MEANS FOR REFRIGERATING APPARATUS

Henry A. Smith, Phillipsburg, N. J., and John Kirgan, Brooklyn, N. Y., assignors to Ingersoll-Rand Company, Jersey City, N. J., a corporation of New Jersey

Application December 23, 1938, Serial No. 247,358

10 Claims. (Cl. 62—152)

The present invention relates to a control means for a refrigerating apparatus and more particularly it relates to a water refrigerating apparatus having an evacuator for each chamber of a multi-chamber evaporator wherein means are provided to render the evacuators ineffective and the corresponding chambers inactive for refrigerating purposes. When ever 5 centrifugal evaporators are employed to remove vapor from a water evaporator, it is often desirable to render a chamber inactive due to a change in the load on the apparatus, and, to this end, dampers are interposed between the evaporator and the evacuators. When such a damper 10 is closed, the respective evacuator is rendered ineffective to remove water vapor from its associated chamber. The objection to such arrangement, when employed with an evaporator having a common cool refrigerant outlet for all the 15 chambers in the evaporator, is that the cooled refrigerant coming from an active chamber is mixed with the non-cooled or heated refrigerant coming from an inactive chamber, with the result that the apparatus becomes relatively inefficient.

It is, accordingly, an object of the present invention to provide means for the cooled refrigerant in all chambers of an evaporator whether active or inactive.

It is another object to provide means whereby the vapor in an inactive chamber of an evaporator may be evacuated by an evacuator associated with an active chamber.

Another object is to provide means in a multi-chamber refrigerating apparatus to render a chamber inactive.

A further object is to provide inter-connected dampers whereby the number of active evaporator chambers of a multi-chamber refrigerating apparatus may be varied without heating 40 the refrigerant flowing from the active chambers.

Still another object is to provide refrigerating apparatus wherein one evacuator may remove vapor from one or more chambers of an evaporator.

These and other objects will be apparent from the following description of which the drawing forms a part and wherein is illustrated a refrigerating apparatus incorporating the present invention.

The refrigerating apparatus comprises an evaporator 1 which is divided into two chambers 3 and 5 by the wall 7 which extends from the top wall of the evaporator 1 and terminates at a point substantially near the bottom wall of

the evaporator. For the sake of convenience, a two chamber evaporator has been illustrated but it is apparent that any number of chambers may be formed in the evaporator without departing from the scope of this invention. 5

The refrigerant employed in this particular embodiment is water which is admitted to the chamber 3 by the conduit 9 and to the chamber 5 by the conduit 11. The refrigerant, after chilling, is removed from the evaporator through the 10 conduit 13 which opens into a well 15 formed at the bottom of the chamber 5. Since the wall 7 does not extend to the bottom wall of the evaporator 1, refrigerant may flow from chamber 3 into chamber 5 and thus to the outlet conduit 15 13. The conduit 13 leads to the point where the cooling effect of the refrigerant is to be utilized.

Both chambers 3 and 5 are provided with vapor outlet ports 17 and 19 through which water 20 vapor is removed by the evacuators 21 and 23 associated with the ports. These evacuators are of the centrifugal type and are directly connected by the shaft 25 to the driving motor 27. Since the shaft 25 actuates both evacuators, it 25 is apparent that whenever the motor 27 is operated, both the evacuators will function to remove water vapor from their respective chambers. A common condenser 29 receives the water vapor removed from the evaporator chambers 30 by the evacuators 21 and 23.

With this construction, so long as the refrigerating load remains constant, both evacuators will withdraw vapor from the evaporator chambers and, since the evacuators are identical, approximately the same vapor pressure will exist in both chambers 3 and 5. However, if the demand for refrigerant should fall, it is necessary to, in some way, stop the removal of vapor from at least one chamber in order that no excessive 40 refrigeration of the water in the chambers shall occur. To this end a damper 31 is pivoted on pin 33 in the vapor outlet port 19. When the damper 31 is in the position which opens the vapor port 19, the evacuator 23 can remove vapor 45 from the chamber 5. However, when the damper is in the position shown in the drawing, the evacuator, even though operating, cannot remove vapor from the chamber 5. It is thus apparent that, if no other means were provided, 50 the refrigerant sprayed into chamber 5 would be removed therefrom at the same temperature as it entered.

Under such conditions the refrigerant flowing through the outlet conduit 13 would be at the 55

temperature determined by the temperature of the cooled refrigerant flowing from chamber 3 and the temperature of the refrigerant entering through conduit 11. This would result in a comparatively inefficient operation of the apparatus.

In order to obviate this fault, partition 7 is provided with an aperture or vapor port 35 which would permit communication between the chambers 3 and 5 at all times were not damper 37 provided. The damper 37 is designed to pivot about pin 39 fastened to the partition wall 7. When the damper 37 is open, it is desirable to have damper 37 closed and when damper 37 is closed, the damper 37 should be open. For this reason, an appropriate linkage is provided which comprises an arm 41 securely fastened to damper 37, an arm 43 securely fastened to damper 37 and a lever 45 pivotally connected to these arms.

At the pivot between arm 41 and lever 45 the actuating rod 47 is likewise pivoted. This rod extends through the wall of evaporator 1 and is threaded at its outer end. At the point where the rod 47 passes through the wall of evaporator 1 packing 49 held by the packing nut 51 prevents leakage of any vapor from the chamber 5 around the rod 47. A casing 53 supported by the evaporator wall surrounds this rod and supports the hand wheel 55 which threadedly engages the rod 47. Although the hand wheel 55 is free to rotate, it is held from longitudinal movement by the projection 57 formed as a part of the casing 53. It will be observed that when the hand wheel 55 is rotated, it will move the rod 47 longitudinally since it threadedly engages the rod 47. When the rod 47 is in its innermost position, as shown in the drawing, the damper 37 is closed and the damper 31 is open. In order to open the damper 31 and close the damper 37, the rod is moved outwardly from the evaporator wall by appropriate rotation of the hand wheel 55.

It will thus be seen that means for opening and closing the dampers, while maintaining proper coordination of the dampers, is provided.

Obviously, this invention may be modified by those skilled in the art without departing from the scope of this invention and the invention is not to be limited save as defined in the appended claims.

We claim:

1. In a refrigerating apparatus, an evaporator a wall having a vapor port therein dividing the evaporator into two chambers and extending substantially to the bottom of said evaporator, means defining a vapor outlet port for each chamber, a separate evacuator for each chamber to remove vapor from the chambers through said vapor outlet ports, means to supply refrigerant to each chamber, a refrigerant outlet conduit for the evaporator, a damper for the wall vapor port, a damper for a vapor outlet port, levers connecting said dampers, and means to operate said levers to open and close said ports.

2. In a refrigerating apparatus, an evaporator, a wall having a vapor port therein dividing the evaporator into two chambers and extending substantially to the bottom of said evaporator, means defining a vapor outlet port for each chamber, a separate evacuator for each chamber to remove vapor from the chambers through said vapor outlet ports, means to supply refrigerant to each chamber, a refrigerant outlet conduit for the evaporator, a damper for the wall vapor port, a damper for a vapor outlet port, means to operate said dampers to open and close said

ports so arranged that when the vapor outlet port is closed said wall port is opened.

3. In a refrigerating apparatus, an evaporator, a wall having a vapor port therein dividing the evaporator into two chambers and extending substantially to the bottom of said evaporator, means defining a vapor outlet port for each chamber, a separate evacuator for each chamber to remove vapor from the chambers through said vapor outlet ports, means to supply refrigerant to each chamber, a refrigerant outlet conduit for the evaporator, a damper for the wall vapor port normally closed when all the evacuators are functioning, a damper for a vapor outlet port normally open to enable the evacuator to withdraw vapor from the associated chamber adapted on closing to render the evacuator inoperative, and means to operate said dampers to open and close said ports so arranged that whenever said vapor outlet port is closed rendering its evacuator inoperative said wall vapor port is open to permit communication between the vapor space in said chambers.

4. In a refrigerating apparatus, an evaporator, a wall having a vapor port therein dividing the evaporator into two chambers and extending substantially to the bottom of said evaporator, means defining a vapor outlet port for each chamber, a separate evacuator for each chamber to remove vapor from the chambers through said vapor outlet ports, means to supply refrigerant to each chamber, a refrigerant outlet conduit for the evaporator, a damper for the wall port, a damper for a vapor outlet port, and means to operate said dampers to open and close said ports including a threaded rod extending into the evaporator, a casing mounted on the evaporator through which said rod extends, a threaded handle engaging the threaded rod and rotating without longitudinal movement on said casing whereby said rod may be moved longitudinally, and a series of inter-connecting levers connecting said rods to said dampers arranged to move said wall port damper to open said wall port and to move said vapor outlet damper to close said vapor outlet damper upon longitudinal movement of the rod into said evaporator and to open said vapor outlet damper and close said wall port damper upon longitudinal movement of the rod away from said evaporator.

5. In a refrigerating apparatus, an evaporator, a wall having a vapor port therein dividing the evaporator into two chambers and extending substantially to the bottom of said evaporator, means defining a vapor outlet port for each chamber, a separate evacuator for each chamber to remove vapor from the chambers through said vapor outlet ports, means to supply refrigerant to each chamber, a refrigerant outlet conduit for the evaporator, a damper for the wall port, a damper for a vapor outlet port, and means to move said dampers to open and close said ports including longitudinally movable means extending into an evaporator chamber, means mounted on the evaporator to support the said movable means, means to move said movable means, and means connecting said movable means and the dampers so arranged that when one damper is in its closed position the other is in its open position whereby one chamber may be rendered inactive and the remaining evacuator may remove vapor from both said chambers.

6. In a refrigerating apparatus, an evaporator, means dividing said evaporator into two chambers arranged to enable refrigerant to flow from

one chamber to the other, a port in the first said means, means defining a vapor outlet for each chamber, evacuating means for each chamber to remove vapor through each vapor outlet, means to close one of said vapor outlets and render the associated evacuator ineffective, a second means to close said port, and means to operate the first closing means and the second closing means so arranged that when one of said closing means is in its closed position the other is in its non-closing position.

7. In a refrigerating apparatus, an evaporator, means dividing said evaporator into two chambers arranged to enable refrigerant to flow from one chamber to the other, a vapor port in the first said means, means defining a vapor outlet for each chamber, evacuating means for each chamber to remove vapor through each vapor outlet, means to close one of said vapor outlets and render the associated evacuator ineffective, a second means to close said vapor port, and means to operate both said closing means including means connecting both said closing means, and longitudinally movable means associated with said connecting means adapted upon movement to move one of said closing means to its closing position while moving the other to its non-closing position.

8. In a refrigerating apparatus, an evaporator, means dividing said evaporator into two chambers arranged to enable refrigerant to flow from one chamber to the other, a vapor port in said dividing means, means defining a vapor outlet for each chamber, evacuating means for each chamber to remove vapor through each vapor outlet, primary means to close one of said vapor outlets and render the associated evacuator ineffective, secondary means to close said vapor port, and means to move said primary closing

means to the closed position and the secondary closing means to the open position including means connecting said primary and secondary closing means, means to move said connecting means, and means to move the last said means. 5

9. In a refrigerating apparatus, an evaporator, means dividing said evaporator into two chambers arranged to enable refrigerant to flow from one chamber to the other, a vapor port in said dividing means, means defining a vapor outlet 10 for each chamber, evacuating means for each chamber to remove vapor through each vapor outlet, primary means to close one of said vapor outlets and render the associated evacuator ineffective, secondary means to close said port, 15 and means to move said primary closing means to the closed position and the secondary closing means to the open position comprising a connecting means for the primary and secondary closing means, means to move the connecting 20 means, means on the evaporator to support the last said means, and means to move the last said means.

10. In a refrigerating apparatus, an evaporator, means to divide the evaporator into a plurality of chambers arranged to enable refrigerant vapor to flow from one chamber to another, a vapor port in said dividing means, a vapor outlet port for each chamber, a separate evacuator for each chamber to remove vapor from the 25 chambers through said vapor outlet ports, means to supply refrigerant to each chamber, a refrigerant outlet conduit for the chambers of the evaporator, means to close a vapor outlet port, means to close said vapor port, and means to 30 open and close the vapor outlet port closing means and said vapor port closing means. 35
